UNITED STATES PATENT OFFICE

2,177,680

AUTOMATIC WINDER

Edward J. Abbott, Wilton, N. H., assignor to Abbott Machine Company, Wilton, N. H., a corporation of New Hampshire

Application February 12, 1936, Serial No. 63,542

20 Claims. (Cl. 242—35.6)

This invention relates to automatic winding machines, or winding machines having certain automatic features, and has for its principal object to provide a winding machine having a number of winding units and a traveling magazine which can be loaded at a given point in its path of travel, and set to traveling around the machine, encountering the several winding units successively and replenishing their several masses in an automatic manner. Thus a principal advantage of the invention is avoidance of necessity for the operator to travel about the machine in aid of replenishing the supply masses of the winding units, or of conveyance of all of the winding units past the operator or replenishing mechanism.

The invention further aims to provide improved stopping and starting mechanism adapted for use in conjunction with automatic replenishment of the supply mass of a winding unit, improved mechanism for finding the broken or exhausted end of yarn upon the surface of a wound package, for associating the found end and the end of yarn of a supply mass, uniting these ends and delivering a tied-in supply mass to the supply mass holder of a winding unit, and to provide improved mechanism for beginning winding again after these operations. The invention further aims to simplify the construction of automatic winding machines. Other objects of invention and advantages will be apparent from this specification and its drawings, wherein the invention is explained by reference to a preferred embodiment.

In the drawings:

Fig. 1 is a vertical transverse sectional view of a multiple winding machine and its traveling magazine and replenishment mechanism, according to this invention;

Fig. 2 is a plan view of one end portion of the machine, with certain parts broken away and other parts omitted for clarity of illustration;

Fig. 3 is a side elevation of a portion of the winding machine comprising portions of four winding units, the relative positions of certain parts of the traveling replenishing mechanism being indicated thereon;

Fig. 4 is a horizontal section on the line 4—4 of Fig. 1, showing the magazine, magazine tripping mechanism, knotter and associated parts;

Fig. 5 is a vertical section on the line 5—5 of Fig. 4, showing part of the magazine tripping mechanism;

Fig. 6 is a side elevation of the knotter;

Fig. 7 is a side elevation of the yarn-guiding plate of the knotter showing the yarn-crossing

mechanism and knot-stripping arm mounted thereon, with the position of the knotter cam indicated in broken lines; and

Fig. 8 is a plan view of the knotter without the cover for the knotter cam.

The illustrated machine is shown as provided with a stationary frame consisting of a series of vertically and transversely arranged members 11, tied together longitudinally of the machine by rails 12, 13, 14 and 15, these frame members and rails serving to support the non-traveling winding devices of the machine, and serving as guides for the traveling magazine and replenishing mechanism.

Drive shafts 16, extending longitudinally on opposite sides of the machine, are mounted in suitable bearings 17 on the rails 13, and carry between these bearings suitable winding package driving elements shown at 18 as comprising rolls having crossed yarn traversing grooves 19. The patent to Reece No. 1,749,355 may be referred to for a description of these rolls. Instead of the yarn-guiding grooves 19 being crossed, other forms of traverse devices may be provided, for example non-crossed yarn grooves on the rolls 18, or separate traverse devices located in proximity to the rolls 18 which would then not have yarn-guiding grooves.

Each winding unit is shown as including a winding package spindle 21, pivotally mounted at 22 to a package-carrying arm 23, so as to be adapted to swing outwardly for endwise doffing of the wound package 25 from the spindle. The several winding package-carrying arms 23 are conveniently mounted for swinging about a common longitudinal shaft 27 so located that the winding package 25 of each unit is adapted to rest upon the surface of the package driving roll 18 of that unit. The supply mass holders for the winding units are shown as comprising collars 28 rotatably mounted upon a longitudinal shaft 29 and carrying radially arranged bobbin pegs 30, adapted to be moved into a yarn-delivering position and into a bobbin-dumping position.

In each winding unit, the yarn coming from any suitable bobbin 33 on one of the pegs 30 of the supply mass holder, passes upwardly between the frictional elements of a tension device 34 which is mounted upon the rail 14, then over a wire detector element 35, into the traversing groove 19 of the winding package drive roll 18, and thence onto the winding package 25.

Each winding unit is shown as provided with a package lifting mechanism including a vertical rod 38 adapted to move vertically in suitable sup-

ports 37 and 39, and normally urged upward by a compressed spring 40, but normally restrained against such upward movement by a latch 41 engaging a projection 42 on the rod 38. This rod 5 carries a yoke 44 into which extends a projection 45 from the package-carrying arm 23. A rod 38, 10 extends upwardly from the yoke 44 in prolongation of the rod 38, and is pivotally connected at its upper end to a rocker arm 47 which is pivotally mounted at 48 and carries at its outer extremity a roller 49 adapted to cooperate with the package-resetting mechanism of the traveling replenishing mechanism.

The latch 41 is shown as formed as a bell crank pivotally mounted at 52 and carrying a dog 53 pivotally connected thereto at 54. The detector wire 35 is normally held in the full-line position of Fig. 1 by the tension of the winding strand, and in this position a connecting link 57 between the detector wire and dog 53 holds the dog 53 in the inclined position shown in full lines in Fig. 1, free from the oscillating path of motion of a rocker 59. Upon breakage or exhaustion of the winding strand, the detector 25 wire 35 falls outwardly to the dotted line position of Fig. 1, and acts through the connecting link 57 to swing the dog 53 into the path of the rocker 59, thereby causing the dog 53 to turn the latch 41 and move it out of engagement with the projection 42 on the rod 38. This permits the compressed spring 40 to lift the rod 38, yoke 44, and through the action of the yoke 44 upon the projection 45, lift the package-carrying arm 23 and carry the winding package spindle and package to a position such as shown for the right-hand package in Fig. 3. The rockers 59 for the several winding units are conveniently fastened to a common rocker arm shaft 62 having fast thereon an arm 63 which is oscillated by a connecting link 64 from a suitable crank pin 65, shown in Fig. 1 as driven by reduction gearing 66, 67 from a motor 69.

The traveling magazine and replenishing mechanism, shown in elevation and partly in vertical section in Fig. 1, includes a casing 71 containing a suction fan 72 driven by an electric motor 73 and adapted to create a partial vacuum in a vertical tube 74 extending centrally from the casing 71. A curved suction tube 75 has its lower end extending within the upper portion of the tube 74 and suitably spaced therefrom by a spacer member 76, and then extends in a curve to a suction nozzle 77 positioned above the level of the tops of the winding packages. This curved suction tube 75 carries near its nozzle end a bracket indicated at 79 carrying pivoted yokes 80 in which are mounted flanged wheels 81 adapted to ride on the upper rail 12 of the frame of the machine. A frame element 84 extending down from the casing of the motor 73 of the traveling unit carries at its lower end a wheel 85 adapted to bear against the lower rail 15 of the stationary frame. Suitable electric conductor rails 86, shown as three in number, are provided on the inner face of the rail 15 and are insulated from each other and from the rail, and suitable electric brushes 87, carried by an insulating bracket 88 on the member 84 are adapted to cooperate with the stationary electric rails 86 in supplying current for operating the several mechanisms of the traveling units, including the suction fan 72 referred to above.

For causing the traveling magazine and replenishing unit to move around the machine into 75 association with the several winding units suc-

cessively, the opposite ends of the machine are provided with sprocket wheels, of which one is shown at 90 in Fig. 2, one of these sprocket wheels being driven by any suitable means, and acting to drive a conveying chain 91 in an endless path around the machine, the traveling unit being connected to this chain 91 by a link 92 which is pivoted to the chain and to a projection 93 from the bracket 79. It is preferred that provision be made for stopping and starting the motion of the chain 91 and traveling units without stopping the driving of the winding package drive rolls 18, and any suitable stop mechanism may be provided for this purpose.

The magazine of the traveling unit comprises a plate 97 adapted to rotate about the central tube 74 and carrying at its periphery a series of cylindrical bobbin holders 98, each slotted at 99 and each provided with a bottom trapdoor 100. The plate 97 is normally restrained against rotary movement about the tube 74 by engagement of a latch 102 with one of a series of pegs 103 corresponding in number to the bobbin holders 98. The plate 97 engages on its under face a rotary disk 105 which is constantly driven by engagement of its internal gear teeth 107 with a driving pinion 108 rotated by a reduction gearing and motor unit 109 which is mounted upon a stationary collar 110 on the tube 74. Tripping of the latch 102 therefore permits the constantly rotating friction plate 105 to rotate the magazine plate 97 and its bobbin holders 98 through an arc occupied by one bobbin holder.

The machine includes means for releasing the latch 102 and causing the aforesaid rotation of the magazine each time the magazine encounters a winding unit. As indicated in Fig. 5, a sleeve 110, fastened to a stationary flange 110, serves as a bearing for a vertical shaft 111 with which the latch 102 is integral. Fast on the lower end of the shaft is a collar 112 which is acted upon by a coil spring 113 to urge the latch 102 into latching position. The collar 112 carries a rod 114, extending, as shown in Fig. 1, into the vicinity of the rail 14. Adjacent to each winding unit is provided a stationary pin 115, adapted to detain and turn the rod 114, thereby swinging this rod and the latch 102 to their dotted line positions of Fig. 4 and releasing the magazine in time for the magazine to turn and discharge a bobbin to an empty peg 30 of the winding unit.

A rim 112 on the stationary flange 110 supports the trapdoors 100 of the several bobbin holders, but terminates at a point where a bobbin holder 98 is nearest to one of the stationary winding units, there allowing the trapdoor 100 to drop to the vertical position shown for the trapdoor 100 at the left of the magazine of Fig. 1, in position for the bobbin from the bobbin holder 98 to drop down a chute 115 and be received by the upturned peg 30.

The suction nozzle 77 is provided at its opposite ends with bearings 117 for an end-finding package-rotating roll 118 which is shown as driven through a pulley 119, belt 120 and pulley 121 from a motor 122 mounted upon the curved tube 75. The curved tube 75 is provided with a slot 124 connecting the opening of the nozzle 77 with the space between the tube 75 and the larger suction tube 74, so that an end of yarn found by the suction nozzle 77 upon the face of a package is adapted to travel along this slot 124 in the tube 75. This movement of the yarn carries it to the tying bill or bills of a knot tyer 125 which is mounted in the space between the 75

5 rotary series of bobbin holders 98 and the central suction tube 74.

10 The knot tyer 125 may be of any desired type, for example that described and claimed in the copending patent application of Edward J. Abbott for Knotter, Serial No. 63,541 filed concurrently herewith, but preferably as shown in Fig. 4 is constructed as described and claimed in the copending patent application of Edward J. Abbott for Knot tyer, Serial No. 63,540 filed concurrently herewith. Referring to Fig. 4, the knot tyer 125 and driving electric motor 126 are supported by a bracket 127 from the central suction tube 74. The knot tyer 125, which is adapted to operate according to the general principle disclosed in the United States Patent to Edward J. Abbott and Joseph E. Ring, No. 1,965,023, includes cooperating rotary tying bills 130, 131 driven through gears 133, 134 and 135, 136 respectively from a main knotter shaft 137 carrying a notched friction plate 138. A cooperating rotary drive element 139 carrying friction material 140 on its face is pressed against the notched plate 138 by a spring 141, and is constantly driven through gear teeth 142 on its periphery by a train of gearing 143, 144 connected to the shaft 145 of the electric motor 126. A pivotally mounted latch 147 normally engages the notched plate 138 and restrains it against 30 rotary movement by the driving mechanism, but rotation of the magazine causes one of a series of projections 151 on the plate 97 to lift a pivotally mounted element 152 (Fig. 1) and raise a lifter rod 153 attached thereto and to the pivoted latch 147, thereby disengaging the notched plate 138 and permitting this plate and the shaft 137 to be turned through one revolution by the knotter-driving mechanism. As more fully disclosed in the said United States application for 40 Knot tyer Serial No. 63,540 filed concurrently herewith, a cam 156 on the main knotter shaft 137 is provided with a cam groove 157 adapted to actuate a pair of yarn positioning and crossing members or pockets 158^a and 158^b and is further provided with a cam groove 159 adapted to actuate a suitable knot-stripping arm 160.

45 As indicated in Fig. 7, a side plate 180 on the knotter carries a pivotal support 181 for the lower end of a lever 182 which carries a cam follower 183, engaging in the groove 157 of the knotter cam 156. The yarn-guiding and crossing member or pocket 158^a is carried by a member 185 which is mounted on a pivot 186 on the plate 180, and the yarn-guiding and crossing member or pocket 158^b is carried by a link 187 pivoted at 50 188 to the upper end of lever 182 and provided with a slot 189 on which it slides on the pivot 186. A pin 191 fast on member 185 and engaging in a slot 192 in link 187 acts to swing member 185 in a clockwise direction about the pivot 186 when link 187 is shifted to the left by the action of the cam 156. The yarn-guiding and crossing pockets 158^a and 158^b cross the two yarns in the path of the bills 130 and 131 during 55 the first rotation of these bills, and then return to their initial position, with the result of causing the bills to tie each yarn into a single knot inclusive of only a single thickness of the other yarn. During the second revolution of the bills, 60 when the yarns have been grasped by the bills and cut off to form the tails of the knot, the knot-stripping arm 160, which is pivoted at 193, is actuated by its cam follower 194 and cam groove 159 to swing to the dotted line position 65 of Fig. 7, pull the knot off the bills and tighten 70 75

it before the bills finally release the tails of the knot.

75 The finding of an end of yarn upon the wound package 25 by the suction nozzle 77, and the consequent travel of the found end along the slot 124 in the tube 75 causes this found end to be laid into the yarn-positioning and guiding member or pocket 158^a, the yarn being directed toward this member or pocket by a notch 197 in plate 180, and by a divider plate 198 which definitely prevents this yarn from going into the other pocket 158^b. Approximately simultaneously with the end-finding, the rotation of the magazine through an arc representing one of the bobbin-holding compartments 98 carries the end of a 15 replenishment supply strand extending from a bobbin in this holder 98, and held by suction in the space between the suction tubes 74 and 75, into the yarn positioning element 158^b. This movement of the yarn is aided by the upper edge 180^a of plate 180 which holds the yarn out of the knotter until it reaches and drops into the slot 199 therein. When the two yarns are thus positioned, the knotter tripping mechanism, including the lifter rod 153 and latch 147 are actuated 20 as described above, to cause the knotter bills 130, 131, and yarn positioning elements 158^a and 158^b, to tie the knot and to cause the knot-stripping element 160 to pull the tied knot from the bills. 30

35 The rotation of the magazine to bring the yarn of a new bobbin into the knot-tying mechanism and operate the knotter-tripping mechanism brings the bobbin holder 98 of which the bobbin is being tied into association with the bobbin chute 115, permits the trapdoor 100 at the bottom of the bobbin holder 98 to open, and consequently discharges the tied-in bobbin to the bobbin-holding pegs 30 of the winding unit.

40 The machine preferably includes automatic means for discharging the cores of bobbins which have been subjected to unwinding in the winding units, thus to prepare each winding unit for the reception of a fresh tied-in supply bobbin. A preferred form of such means is illustrated as 45 comprising an arm 170 projecting from the frame member 84 of the traveling magazine unit, and having a portion 171 bent backward from the direction of travel of the magazine unit and positioned to contact a downwardly extending 50 bobbin peg 30 and swing this bobbin peg and its associated collar 28 through an arm of 120°. This rotation of the collar 28 brings the bobbin peg 30 which has just held a bobbin into a downwardly inclined position in which the bobbin 55 can fall by gravity off the peg, and at the same time position the neighboring bobbin peg 30 on the collar 28 with respect to the bobbin chute 115 of the approaching magazine unit. The machine preferably includes a pair of endless conveyor 60 belts 175, adapted to catch the discharged bobbins from the peg 30, carry them to one end of the machine, and drop them into suitable receptacles 176.

65 In the course of the travel of the magazine and replenishing units about the machine, in the direction of the arrow X in Fig. 2, the traveling unit encounters wound packages 25 which have been raised to the position of the right-hand wound package in Fig. 3 as the result of exhaustion or breakage of their supplies. In order to position the wound package 25 with respect to the unwinding roll 118 and end-finding nozzle 77, and subsequently to position the package for further winding and reset the stop mecha- 70 75

nism of the unit, the traveling magazine is provided with a cam 180 adapted to cooperate with the rollers 49 of the rocker arms 47 of the successive winding units. Referring to Fig. 3 in which the outline of this cam 180 is indicated in dotted lines, the cam 180 is provided with an inclined forward portion 181 adapted to strike the rocker arm of a winding unit and raise roller 49 an amount sufficient to depress the rod 38a 5 and yoke 44 against the action of the spring 40 to a point at which the wound package 25 lies below the path of travel of the unwinding roll 118 and suction nozzle 77, but still out of contact with the package drive roll 18. 10

15 A level portion 182 of the cam 180 then acts through the rocker arm roller 49 to hold the wound package 25 in this position until the unwinding roller 118 has reached a position approximately directly above the wound package 20 25, whereupon the rocker arm roller 49 drops into a depressed portion 183 of the cam 180 with a result that the spring 40 is free to act through the package-carrying arm 23 to raise the package into contact with the unwinding roller 118. 25

25 During the travel of the magazine represented by the length of the depressed portion 183 of the cam 180, the end of the yarn upon the wound package 25 is being found, and this found end and the end of the replenishment supply bobbin 30 are being positioned for tying. An inclined portion 184 on the cam 180 then raises the rocker arm roller 49 and restores the wound package 25 to its midway position out of contact with both the unwinding roller 118 and package drive roll 35 35 18, a level portion 185 on the cam 180 acting to retain the package in this position during a period in which the magazine is rotated to operate the knot tyer 125 and drop the tied-in bobbin. A further inclined portion 186 on the cam 180 40 then contacts with the rocker arm roller 49 to plow this arm up sufficiently to depress the rod 38 still further and bring the projection 42 thereon below the cooperating latch 41 of the stop mechanism of the unit, at the same time allowing 45 the wound package 25 to contact with the rotating package drive roll 18. The highest and final level 187 on the cam 180 retains the rocker arm 47 in the position of Fig. 1 until the winding package 25 has been accelerated to its full 50 speed and the winding yarn put under tension, and the pivoted detector wire 35 brought to its normal running position by the tension of the winding yarn. The stop mechanism is thus held 55 inoperative by the traveling magazine unit during a period in which the winding is begun and the detector mechanism restored to its normal running position.

Since the operation of each of the several 60 mechanisms of the machine has been explained, the operation of the machine as a whole will be readily apparent. The operator of the machine loads the magazine with replenishment supply bobbins when the magazine is at one end of the machine, placing the ends of yarn of these several bobbins in the space between the suction tubes 14 and 15, then causes the magazine to travel in its path into association with the winding units of the machine successively. In this travel, each winding unit is automatically supplied with a fresh supply bobbin tied in to the strand of the wound package of the unit, and the wound package again set to winding from its new supply. If desired, the winding machine 65 may be built of such length that the traveling magazine can make a complete course around

the machine with one filling of its several bobbin holders 98. Or, if desired, the machine may have double the number of winding units which are served by one filling of the traveling magazine, and the magazine in that case be filled at 70 bobbin stations at opposite ends of the machine.

It will readily be apparent that the number of bobbin holders on the traveling magazine can be increased.

It should be understood that the present disclosure is for the purpose of illustration only and that this invention includes all modifications and equivalents which fall within the scope of the appended claims.

I claim:

1. A winding machine having therein a plurality of stationary winding units each including a holder for a supply strand mass, a traveling magazine adapted to carry a plurality of supply strand masses and to discharge said supply 20 masses successively to the said holders of the winding units, means traveling with the magazine for uniting supply mass strands to the strands of the successive winding units, means for causing the magazine to discharge supply 25 strand masses to the said holders of the successive units, and means controlled by the travel of the magazine for starting the winding units successively following delivery thereto of a supply mass by the magazine and uniting of a 30 supply mass strand to the strand of the winding package.

2. A winding machine having therein a plurality of stationary winding units each including a holder for a supply strand mass, a traveling magazine adapted to carry a plurality of supply strand masses, means for associating the strands of the wound packages of the winding units and the strands of the supply masses of the magazine, strand-uniting mechanism traveling 40 with the magazine for uniting the associated strands, and means for delivering the tied-in supply strand masses from the magazine to the said holders of the units successively.

3. A winding machine having therein a plurality of stationary winding units, each including a holder for a supply strand mass, a traveling magazine adapted to carry a plurality of supply strand masses, a suction conduit traveling with the magazine and into which the ends 50 of a plurality of supply strands in the magazine can be inserted and thereby held in condition for uniting, strand-uniting mechanism associated with the magazine for uniting the thus held strands of the magazine successively to the 55 strands of the wound packages of the successive winding units, said uniting mechanism acting to cut off the suction-held end of each supply strand, and means for delivering the tied-in supply strands from the magazine to the said 60 holders of the units successively.

4. A winding machine having therein a plurality of stationary winding units, and a traveling tender unit adapted to present itself periodically at an operator's station, the traveling tender unit including means for delivering supply strand masses to the several winding units, and including a suction device having an opening into which the operator can put the ends of a plurality of supply strands to be carried to the 70 winding units.

5. A winding machine having therein a plurality of stationary winding units each including a winding package drive roll and stop mechanism including means for yieldingly elevating the

winding package in the event of failure of the winding strand, a traveling tender unit including an end-finding nozzle and unwinding roll, the end-finding roll moving in a path above the package drive rolls of the winding units, and means associated with the traveling tender unit for lowering an elevated package to below the path of the unwinding roll and then releasing the thus lowered package to permit the said elevating means to hold the package against the unwinding roll.

6. A winding machine having therein a plurality of stationary winding units, a magazine adapted to travel along the winding machine and to carry a plurality of supply strand masses and deliver the same successively to the winding units, means traveling with the magazine for rotating the packages of the successive winding units in an unwinding direction, means for uniting the thus unwound ends of strand to supply strand masses carried to the winding units by the magazine and means for presenting the strands of said supply masses successively to the said uniting means.

7. A winding machine having therein a plurality of stationary winding units, a magazine adapted to travel along the winding machine and to carry a plurality of supply strand masses and deliver the same successively to the winding units, suction means traveling with the magazine for securing the ends of strand of the packages of the winding units, means for uniting the said ends of strand to supply strand masses carried to the winding units by the magazine and means for presenting the strands of said supply masses successively to the said uniting means.

8. A winding machine having therein a plurality of stationary winding units, a magazine adapted to travel along the winding machine and to carry a plurality of supply strand masses, suction means associated with the magazine for holding the ends of the strands of the supply masses carried by the magazine, and means for uniting the said strands to the strands of the successive winding units.

9. A winding machine having therein a plurality of stationary winding units, a magazine adapted to travel along the winding machine and to carry a plurality of supply strand masses, the magazine including means for holding ends of strand of supply strand masses carried by the magazine, strand-uniting means associated with the traveling magazine, and means for automatically placing in the uniting means the ends of strand of the winding units and the ends of strand of the strand masses carried by the magazine.

10. A winding machine having therein a plurality of stationary winding units, a magazine adapted to travel along the winding machine and to carry a plurality of supply strand masses, the magazine including means for holding ends of strand of supply strand masses carried by the magazine, means associated with the magazine for automatically assembling strands of the packages of the winding units and strands of the supply masses carried to the units by the magazine, and means for uniting the assembled ends.

11. A winding machine having therein a plurality of the stationary winding units, a magazine adapted to travel along the winding machine and to carry a plurality of supply strand masses, the magazine including means for holding ends of strand of supply strand masses carried by the magazine, means for automatically

assembling strands of the packages of the winding units and strands of the supply masses carried to the units by the magazine, and means for uniting the assembled ends.

12. A winding machine having therein a plurality of stationary winding units, a magazine adapted to travel along the winding machine and to carry a plurality of supply strand masses, the magazine including means for holding ends of strand of supply strand masses carried by the magazine, and means for automatically uniting the ends of strand of the winding units and the ends of strand of the strand masses carried by the magazine.

13. A winding machine having therein a plurality of stationary winding units, a magazine adapted to travel along the winding machine and to carry a plurality of supply strand masses, the magazine including means for holding ends of strand of supply strand masses carried by the magazine, means for automatically uniting the strands of the units of the strands of the masses carried thereto by the magazine, and means for automatically starting the winding units to wind following said uniting.

14. A winding machine having therein a plurality of stationary winding units each including a holder for an unwinding supply mass, means for carrying replenishment supply strand masses along the machine to the several units and delivering said masses to the holders of said units, said carrying means including means for holding the ends of strand of the replenishment supply strand masses, and means for automatically uniting said strand masses to the strands of the several winding units.

15. A winding machine having therein a plurality of stationary winding units each including a holder for an unwinding supply mass, means for finding broken or exhausted ends of a strand on the packages of the winding units, means for carrying replenishment supply strand masses along the machine to the several units, and delivering said masses to the holders of said units, said carrying means including means for holding the ends of strand of the replenishment supply strand masses, and means for automatically uniting the replenishment strand masses to the found ends of strand.

16. In a multiple unit winding machine having supply mass holders for the respective winding units, replenishment mechanism comprising a knotter, a magazine movable with relation to the knotter to discharge a replenishment strand mass to a supply mass holder of a winding unit and to deliver the strand of said mass to the knotter, means for constantly urging the knotter to operate, means for restraining the knotter against operating, and means controlled by the movement of the magazine to release said restraining means.

17. In a multiple unit winding machine having supply mass holders for the respective winding units, replenishment mechanism comprising a knotter, a magazine movable with relation to the knotter to discharge a replenishment strand mass to a supply mass holder of a winding unit and to deliver the strand of said mass to the knotter, means for thus moving the magazine, and means controlled by the movement of the magazine to operate the knotter.

18. In a multiple unit winding machine having supply mass holders for the respective winding units, replenishment mechanism comprising a knotter, a magazine movable with relation to

the knotter to discharge a replenishment strand mass to a supply mass holder of a winding unit and to deliver the strand of said mass to the knotter, means for constantly urging the knotter to operate, a latch acting to restrain the knotter against operating, and means associated with the magazine for tripping said latch as the magazine moves.

19. A winding machine having therein a plurality of stationary winding units each including a holder for a supply strand mass, a traveling magazine adapted to carry a plurality of supply strand masses, means for associating a strand of a wound package of a winding unit and a strand of a supply mass of the magazine, strand-uniting mechanism traveling with the magazine for uniting the associated strands, and means for delivering said supply mass from the

magazine to the said supply strand mass holder of the said winding unit.

20. A winding machine having therein a plurality of stationary winding units each including a holder for a supply strand mass, a traveling magazine adapted to carry a plurality of supply strand masses, means for associating a strand of a wound package of a winding unit and a strand of a supply mass of the magazine, strand-uniting mechanism traveling with the magazine for uniting the associated strands, means for delivering said supply mass from the magazine to the said supply strand mass holder of the said winding unit, and means controlled by the travel of the magazine for starting the units to winding successively following delivery thereto of a supply mass by the magazine.

EDWARD J. ABBOTT.
